UNITED STATES PATENT OFFICE.

JOHN H. STACY, OF CLINTONVILLE, WISCONSIN.

COVER FOR ENSILAGE.

1,380,849.

Specification of Letters Patent. Patented June 7, 1921.

Application filed August 4, 1920. Serial No. 401,154.

To all whom it may concern:

Be it known that I, JOHN H. STACY, a citizen of the United States, residing at Clintonville, in the county of Waupaca and 5 State of Wisconsin, have invented a new and useful Cover for Ensilage, of which the following is a specification.

This invention relates to a cover adapted to be placed in a silo for the purpose of 10 covering the ensilage therein and for providing a substantially sealed air space above the ensilage for the retention of heat generated by the ensilage and, consequently, materially reducing the danger of the ensilage 15 becoming frozen in cold weather.

A further object is to provide a cover which, when lifted, will automatically become disengaged from the wall of the silo so that it can be raised easily.

20 A still further object is to provide a cover which is simple and compact in construction and which can be expanded and contracted readily.

With the foregoing and other objects in 25 view, which will appear as the description proceeds, the invention resides in the combination and arrangement of parts and in the details of construction hereinafter described and claimed, it being understood 30 that, within the scope of what is claimed, changes in the precise embodiment of the invention shown can be made without departing from the spirit of the invention.

In the accompanying drawings the preferred form of the invention has been shown.

In said drawings—

Figure 1 is a section through a silo having the present improvements combined therewith, one of the positions of the cover 40 being indicated by full lines and another position by dotted lines.

Fig. 2 is a plan view of the cover.

Fig. 3 is a bottom plan view thereof.

Referring to the figures by characters of 45 reference 1 designates opposed semi-circular sections each of which is provided with parallel pairs of guide cleats 2 secured to the bottom face thereof. The cleats of each pair are connected by cross strips 3 and 50 slidably mounted between the cleats of each pair and held in place by the cross strips 3 are coupling bars 4 extending into the spaces between the opposed pairs of strips or cleats 2, thus to hold the sections 1 flush with each 55 other. The bars 4 can be held against longitudinal movement by pins 5 inserted into

them and bearing against certain of the cross strips 3, as shown. Obviously by removing these pins the sections 1 can be moved longitudinally between the parallel alining 60 strips 2, thus permitting the sections 1 to be separated.

Pivottally connected to the opposed sections 1 at the bottom thereof are downwardly converging links 6 connected to a 65 block 7 constituting a weight and which block is supported under the center of the cover. Centering cords 8 connect the block to opposed portions of the cover, thus to hold said block properly centered and insure the 70 proper actuation of the mechanism. One of the sections 1 is preferably provided with an opening 9 which can be covered by any suitable means but which can be removed whenever it is desired to inspect the ensilage 75 under the cover.

A plate 10 is secured along the straight edge portion of one of the sections 1, being fastened thereto by screws 11 or the like. This plate laps the straight edge portion of 80 the opposed section 1 and has parallel slots 12 slidably engaged by studs 13 projecting from that portion of the section 1 thereunder. Thus it will be seen that the plate 10 serves to close the space between the two 85 sections 1 when they are moved apart.

Guide pins 14 are extended upwardly from the two sections 1 and have heads which can lap opposed tongues 15 extending inwardly from arcuate cover sections 16. 90 These tongues 15 have parallel side edges and the two tongues are disposed in alignment but opposite to each other, they being extended longitudinally along the plate 10 and from the centers of the arcuate portions 95 16. To the inner end of each of the tongues 15 are pivotally connected links 17 and these links are similarly connected, as at 18, to the sections 1 of the cover. A suitable hoisting cable 19 can be connected to 100 the cover in any manner desired and extended upwardly over a supporting sheave 20 within the upper portion of the silo and thence outwardly through the silo as shown in Fig. 1.

Obviously when the cover is held suspended by the cable 19 the block 7, which constitutes a weight, pulls through the links 6 upon the two sections 1 of the cover, thus causing these sections to press together along 110 their straight edges and also to thrust, through the links 17, against the tongues

15 so as to force said tongues toward each other and bring the outer curved edges of the sections 16 substantially in line with the periphery of the sections 1. The cover is thus held contracted and out of contact with the wall of the silo and can be easily moved upwardly or downwardly. When the cover is lowered so as to bring the block 7 against the surface of the ensilage in the silo, the 10 cover will be relieved of the weight of the block as said cover continues to move downwardly. Consequently the links 6 will be caused to move apart at their upper ends during the continued downward movement 15 of the cover while the block 7 is being held and this will result in the two sections 1 being moved apart. At the same time said sections will pull through the links 17 on the tongues 15 and cause said tongues to 20 move apart and the outer edges of the sections 16 to thrust against the wall of the silo. It is preferred to so construct the sections that when the cover is extended its periphery will be circular and contact, 25 throughout its length, with the wall of the silo. With the cover thus located the ensilage will be sealed within the silo and warm air generated will be retained above the ensilage so as to prevent freezing. As 30 soon as the cable 19 is pulled upwardly the cover will contract and can be raised readily off of the ensilage, as will be obvious.

What is claimed is:

1. A cover for ensilage, including opposed 35 relatively movable lower sections, means for covering the space between said sections during said relative movement, opposed top sections movable relative to each other along lines at right angles to the direction of relative movement of the lower sections, a weight suspended below the cover, connections between the weight and the opposed lower sections for holding said sections normally drawn together, means for transmitting motion from the lower section to the upper section for holding said upper sections normally drawn together, and a flexible support for the cover.

2. A cover for ensilage including opposed 50 lower sections movable toward and from each other, means carried by the sections for closing the space between the sections

during such relative movement, a weight below the cover, means operated by the movement of the cover relative to the weight 55 for shifting the lower sections from or toward each other, and means operated by the relative movement of the lower sections for shifting the upper sections toward or from each other, thereby to expand or contract the cover radially.

3. A cover for ensilage including relatively movable lower sections, means carried thereby for closing the space between the sections, opposed upper sections mounted for relative movement along lines at right angles to the direction of relative movement of the lower sections, a weight below the cover, means operated by the relative movement of the weight and cover for shifting 65 the lower sections toward or from each other, and means operated by the relative movement of the lower sections for shifting the upper sections toward or from each other.

4. A cover for ensilage including opposed relatively movable lower sections, downwardly converging links extending therefrom, a weight suspended by the links, means carried by said sections for closing 70 the space between the sections during the relative movement thereof, opposed upper sections mounted for relative movement along lines at right angles to the direction of relative movement of the lower sections, 75 links upon the upper sections and pivotally connected to the lower sections, said links being shiftable by the relative movement of the lower sections for moving the upper sections toward or from each other.

5. A cover for ensilage including relatively movable sections, a weight connected to the sections for holding the cover normally contracted radially, and supporting means connected to the cover for lowering 80 the weight against an obstruction in the path thereof to expand the cover radially.

In testimony that I claim the foregoing as my own, I have hereto affixed my signature in the presence of two witnesses.

JOHN H. STACY.
